UNITED STATES PATENT OFFICE.

WILLIS S. MORSE, OF PHILADELPHIA, PENNSYLVANIA.

TENSION-REGULATOR FOR PRINTING-PRESSES.

1,103,152.

Specification of Letters Patent. Patented July 14, 1914.

Application filed April 18, 1911. Serial No. 621,740.

To all whom it may concern:

Be it known that I, WILLIS S. MORSE, a citizen of the United States, residing in Philadelphia, Pennsylvania, have invented 5 certain Improvements in Tension-Regulators for Printing-Presses, of which the following is a specification.

One object of my invention is to provide means for automatically regulating the tension on a paper web as it is delivered to the printing press, by regulating the retarding force exerted on the spindle of the roll of paper from which said web is fed.

Another object of the invention is to provide tension regulating means of the general type above noted which shall include a device whereby the retarding force on the roll and hence the tension on the paper web may be manually adjusted from a distant part of 10 the press; the invention also contemplating the provision of electrical apparatus whose action may be varied or controlled by the operation of a switch or rheostat to produce the desired retardation.

25 A further object of my invention is to provide a tension regulating mechanism for printing presses which shall include an electrical device for causing variation of the retarding force exerted on the roll of paper, 30 in combination with a web actuated switch or rheostat arm and a contact or contacts cooperating therewith, so arranged that the operation of the electrical apparatus is dependent upon the position of a web-engaging 35 roller connected to said switch or rheostat arm.

These objects and other advantageous ends I secure as hereinafter set forth, reference being had to the accompanying drawings, 40 in which;—

Figure 1, is a side elevation of a portion of a printing press showing my invention as applied thereto; Fig. 2, is a plan of the apparatus shown in Fig. 1; Figs. 3 and 4 are 45 respectively a side and an end elevation of a modified form of my invention, and Fig. 5, is a side elevation of the hand tension adjusting device for use at the front end of the press.

50 In Figs. 1 and 2 of the above drawings, 1 represents portions of the frame of the printing press to which my invention is applied and on this are mounted bearings 2 for the reception of a spindle 3 carrying a roll X

of paper. Fixed in any suitable manner to 55 the end of this spindle is a grooved brake wheel 4 having a pair of brake shoes 5 acting upon it. These shoes are mounted on a pair of oppositely placed levers 6 and these latter each have one arm pivotally connected to 60 a bar 7 mounted on a spindle 8. The other arm of each of the levers has pivotally connected to it a tubular member 9 provided with interior threads and designed to be engaged by a screw 10 fixed to a hand wheel 65 11; it being noted that the thread of one of these members 9 and its coöperating part of the screw is right hand while the thread of the other member and its screw is left hand.

The structure so far described is well 70 known in this art and is commonly employed for exerting any desired retarding action on the spindle or shaft 3 in order to give the suitable tension on the paper web delivered from the roll on said spindle. According to 75 my invention, however, the end of the bar 7, which is connected to the lower of the levers 6 is slotted for the reception of the connecting pin or pivot so that this end of the lever is free to move to a limited extent relatively 80 to said bar. This same arm of the lever is also extended or in any case suitably formed to coöperate with the short arm of a lever 12 pivoted to the frame of the machine at 13 and capable of causing the lower lever 6 to 85 turn on its point of connection with the lower one of the parts 9 as a fulcrum for the purpose of varying the pressure of the brake shoes on the grooved wheel. For actuating 90 this lever 12 I provide an electric motor 14 to whose armature shaft is fixed a pinion 15 meshing with a gear 16 fixed to a threaded shaft 17 which is mounted in suitable bearings as shown. A nut 18 threaded on this shaft is connected to coöperate with an arm 95 19 fixed to a shaft 20 also having fixed to it an arm 21 connected through a rod 22 with the long arm of the lever 12. As is obvious, the operation of the screw 17 by the motor 14 causes turning of the lever 12 on its pivot 100 or fulcrum and thereby actuates the levers 6 and the brake shoes connected thereto.

For governing the action of the motor, I provide a reversing switch and a rheostat 23 electrically connected thereto and to a source 105 of current supply as shown, or in any of the ways well known to this particular art, it being understood that while I preferably use

a rheostat in order to more or less gradually start the motor 14, a switch merely making and breaking the motor circuit may be substituted for said rheostat in some cases without departing from my invention.

- 5 In the form of rheostat shown there is provided a number of contacts 24 mounted concentrically with an elongated contact 25 and two pairs of segmental contacts 24^a and 25^a; there being two bridge pieces 26 and 26^a coöperating with these contacts as indicated in dotted lines in Fig. 1 and carried on an arm 27 fixed to a spindle 28 carried in bearings in the frame 1 of the machine.
- 10 15 The bridge piece 26 is designed to connect either of the contacts 24^a with certain of the contacts 24 while the piece 26^a is placed to connect either of the contacts 25^a with the contact 25. The spindle or shaft 28 has two
- 20 25 arms 29 fixed to its opposite ends and these serve to support a roller 30 designed to engage the paper web after it has passed over a pair of guide or tension rollers 31 and 32 of which the first is commonly known as the compensating roll.

For preventing sudden movements of the arms 29 and their attached parts I provide a dash pot 33 of suitable construction whose piston rod 34 is connected to one of said arms. I likewise connect the latter through a link 35 and a spring 36 to one arm of a lever 37, having an operating rod 38 preferably extended to the front or delivery end of the printing press where it is connected through a lever 59 and a link 50 with a hand operating lever 51 or other device for longitudinally moving it to vary the pressure of the roller 30 upon the web Y of the paper as it passes from the roll X. Said lever 51 may be held in any adjusted position corresponding to a predetermined tension on the paper web by means of a latch 52 and a coöperating notched quadrant 53. With this arrangement of parts, the spindle 3 with its roll of paper is mounted in the bearings 2; the brake wheel 4 having been previously mounted on and fixed to said shaft, and the shoes 5 with their attached parts are then applied to said wheel. The motor circuit being opened at any suitable controlling switch 24^b the paper is then led over the rollers 31, 32, and 30 through the machine in the well known manner, it being understood that the nut 18 is in its mid position on the screw 17.

55 After the press has been set in operation and when the proper tension has been put on the paper web the roll 30 is raised by said web Y to such a height that the contacts 26 and 26^a of the rheostat are at or immediately adjacent to the mid position. If now the current supply switch of the motor be closed, any tightening of the web sufficient to cause the arms 29 to be raised by the action of said web on the roller 30, moves the arm 27 with its contacts 26 and 26^a to such a position that

current is delivered to the motor 14 in the well understood manner. Said motor is so connected that it at once starts and moves the nut 18 on the screw 17 toward itself, thereby so moving the arm 19, shaft 20, arm 21, rod 22, and lever 12 that the lower lever 6 is permitted to move slightly away from the brake wheel 4; it being understood that this lever and its connected parts were previously adjusted by the hand wheel 11 to cause the brake shoe 5 to exert some friction on said wheel. As a result of this action of the motor, the lower brake shoe 5 is caused to bear less heavily on the brake wheel and downward pull through the tubular members 9 upon the upper lever 6 is likewise diminished, thereby also diminishing the pressure of the upper brake shoe. As a consequence, the spindle 3 is permitted to turn more freely in its bearing and the tension on the paper web Y is diminished. As a consequence the roller 30 with its arm 29 drops, thereby bringing the arm 27 and the contact 26 to the mid position on the rheostat, thus stopping the motor 14. If, on the other hand, the tension of the paper web so far slacks as to permit the arms 29 to fall below a predetermined point, the motor is started so as to operate in a direction, the reverse of that indicated, thus so turning the lever 12 that its short arm forces upwardly the coöperating arm of the lower lever 6 and directly presses the lower brake shoe 5 against the brake wheel. At the same time the upper lever 6 is pulled down so that its brake shoe is likewise forced against said wheel. The retarding force exerted on the spindle 3 is thus increased as is also the tension on the paper web Y, until by the raising of the roller 30 and the arms 29, the rheostat arm 26 is returned to its mid position.

The operator in charge of the press may at any time vary the tension on the paper web from his position in front of the press by properly adjusting the pull of the spring 36 on the arms 29 through the rod 38 and lever 37, as he may find to be advisable from his examination of the condition of the printed matter turned out by the press. This feature is particularly valuable in newspaper work, for hitherto it has been customary to regulate the tension of the unprinted paper web from the rear of the machine, although the condition of the work done by the press could only be observed by an operator stationed at the opposite end thereof.

As is obvious, the motor is operated at a greater speed, the greater amount of movement of the arms 29 with the roller 30 from the normal position, for if the contacts 26 and 26^a of the rheostat are rapidly moved from their mid position to the extreme right or left hand contacts, the motor is almost

instantly brought up to full speed and the tension on the paper web is thereby quickly varied as required.

In some instances it may be desirable to replace the brake wheel 4 and its associated parts by other means for exerting a retarding force on the roll spindle and in Figs. 3 and 4 I have shown a relatively simple and compact combination of apparatus 10 for accomplishing the same ends as are secured by the mechanism heretofore described. In this case the roll shaft 3 has fixed to it an armature plate 40 of magnetic material which may be provided with a hub 15 having an annular recess 41 for the reception of the arms of a yoke 42 pivoted to the frame of the machine at 43 and adjustable by means of a hand wheel 44 and a screw 45 to longitudinally move the spindle 20 3 in its bearings for the purpose of bringing the paper roll thereon into any desired position.

An annular brake magnet 46 is mounted on a supporting structure 47 and is preferably slideable so as to be movable toward and from the armature plate 40 after this, with the shaft 3 has been adjusted to any desired position. For this purpose I provide a hand wheel 48 and a screw 49 for 25 moving said magnet on suitably formed guideways on the supporting structure 47, although under certain conditions it may be fixed to its supporting structure. This magnet may be constructed in the form of an electric clutch of which the armature plate 40 forms the movable member and in 30 this instance is connected in circuit with a rheostat 23^a arranged as shown.

As the roll 30 with its arms 29 rises and 40 falls under operating conditions, the movable contact 26 of the rheostat or controller cuts more or less resistance into and out of circuit with the magnet 46, thereby varying the retarding force exerted by it on the 45 revolution of the armature plate 40 and consequently of the shaft 3 with its paper roll. As will of course be understood by those skilled in the electrical art, the winding of the magnet and the amount of the 50 resistance in circuit therewith are so designed that a variation in said amount will cause a material variation in the clutching force exerted by said magnet, with the result that a variation in the amount of resistance in circuit will cause a corresponding variation of the retardation exerted on the armature plate.

By the use of the particular adjusting device shown in Fig. 5, or by some equivalent 60 device, the press operator is enabled to instantaneously set or adjust the tension of the paper web to any desired and predetermined point in order that the press may properly operate with papers of different 65 grades and widths without danger of break-

ing said web. With this idea in view the various notches of the quadrant are placed so that when any one of them is engaged by the latch of the lever, the latter is held in a position corresponding to a certain definite and predetermined tension and the availability of my device for being quickly adjusted to give with certainty any one of a number of predetermined tensions constitutes one of the important advantages of my invention; it being further noted that the operating lever with its latch and quadrant gives visible indication of the tension to which the device is adjusted.

I claim:

1. In a tension regulator for a printing press, the combination of a web roll shaft, a braking mechanism operative on said shaft, means including a member movable in response to variations in the tension of the web to cause the operation of the braking mechanism, a device controllable from the delivery end of the press for changing the adjustment of said movable member, and readily disengageable means for locking said device in any one of a plurality of adjusted positions.

2. In a tension regulator for a printing press, the combination of a web roll shaft, braking mechanism operative on said shaft, means including a member movable in response to variations in the tension of the web to cause the operation of the braking mechanism, and means for retarding the operation of said member and preventing sudden movements of the same.

3. In a tension regulator for a printing press, the combination of a web supply roll shaft, braking mechanism operative on said shaft, means including a member movable in response to variations in the tension of the web to cause the operation of the braking mechanism as the tension of the web varies, manually operable means for adjusting said movable member at will, and means for retarding the operation of said member and preventing sudden movements of the same.

4. In a tension regulator for printing presses, the combination of a web supply roll shaft, a member movable in response to variations in tension of the web fed from said supply roll, mechanism for retarding or permitting the acceleration of the web supply roll shaft, means connecting said member and mechanism and causing the mechanism to be operated in accordance with the variations in the tension of the web, a spring associated with said member, and means whereby the tension of said spring may be adjusted while the movable member is active.

5. In a tension regulator for printing presses, the combination of a web supply roll shaft, a member movable in response to

- variations in tension of the web fed from said supply roll, mechanism for retarding or permitting the acceleration of the web supply roll shaft, means connecting said member and mechanism and causing the mechanism to be operated in accordance with the variations in the tension of the web, a lever having one end extended to a point near the delivery end of the press, a spring connected at one end to said movable member and at its opposite end to said lever, and means for adjusting said lever and spring and holding the latter at any one of a plurality of predetermined tensions.
- 15 6. In a tension regulator for printing presses, the combination of a web supply roll shaft, a brake disk on the roll shaft, a member movable in response to changes in the tension of the web, an electric controller actuated by said movable member, mechanism including an electric device in circuit with said controller for causing variations in the retardation exerted on said brake disk in accordance with changes in the tension of the web, and resistance in circuit with said controller and electric device and arranged

to be varied by said controller as the tension on the web varies.

7. In a tension regulator for a printing press, the combination of a web supply roll shaft, a brake element on the roll shaft, a member movable in response to changes in the tension of the web, an electric device coöperating with said brake element and arranged to cause variations in the retardation exerted on said roll shaft, resistance in circuit with the electric device, and an electric controller in circuit with said electric device and actuated by said movable member, said controller being adapted to insert or cut out resistance in the circuit of said electric device to cause said device to vary the retardation exerted on said roll shaft in accordance with web tension changes.

In testimony whereof, I have signed my name to this specification, in the presence of two subscribing witnesses.

WILLIS S. MORSE.
